WALTER WAIN, OF FULTON, NEW YORK

COCOA COOLING APPARATUS

Application filed March 29, 1927. Serial No. 179,384.

This invention relates to a method of and apparatus for cooling cocoa powder and analogous materials preparatory to the use of such powder in the manufacture of syrups in a more or less plastic state such as chocolate coatings and chocolate fillings for confections and pastry and the like.

The main object is to effect a more thorough and expeditious cooling of the powder than has heretofore been practised by causing the same to pass continuously through tortuous paths in a suitable cooling chamber whereby the temperature is materially reduced in transit from the inlet to the outlet of the apparatus so as to greatly reduce its affinity for moisture, all of which contributes to the production of a better quality of the commercial product in which the powder is used and greatly facilitates the manufacture of such powder into the commercial product.

Other objects and uses relating to specific parts of the invention will be brought out in the following description.

In the drawings:—

Figure 1 is a longitudinal vertical sectional view of an apparatus embodying various features of the invention in which portions of the conducting tubes for the powdered material are shown in section.

Figure 2 is a transverse vertical sectional view taken in the plane of line 2—2, Figure 1.

As illustrated, this apparatus comprises a substantially air-tight rectangular box or housing —1— having a bottom portion, upright side and end portions and a top portion, all bolted or otherwise secured together at their junctions one with the other to form a rigid structure which is reinforced by corner posts —2—, intermediate posts —3— and upper cross bars —4—, the lower ends of the posts —2— and —3— being secured to the bottom of the case by angle irons —5—.

The bottom portion of the case or housing is preferably made of similar laminated sections —6— arranged end to end in the same horizontal plane and preferably extending from side to side of the case with their meeting ends directly under the intermediate posts

—3— while the outer edges of the said sections preferably extend under and beyond the corner posts —2— a sufficient distance to receive and support the upright sides and ends of the case.

In like manner the top portion of the case is composed of similar laminated sections —7— arranged end to end with their meeting ends resting upon and secured to the cross bars —4— and the outer edges of the top sections extended beyond the adjacent cross bars —4— a sufficient distance to overlap upon the upper edges of the upright side and end portions.

The upright sides of the case may also be made of laminated sections —8— arranged edge to edge with their meeting edges overlapping upon the intermediate posts —3— and end posts —2— and secured thereto by any suitable fastening means so as to extend from top to bottom of the case and from end to end thereof.

The upright ends of the case are also composed of laminated sections —9— arranged edge to edge one upon the other vertically and having their meeting edges beveled or overlapped one upon the other to form substantially air-tight joints and also to facilitate the securement of the sections —9— to each other.

As illustrated, all of these laminated sections for the bottom, top, sides and ends are made up of inner and outer layers —10— of wood and an intermediate layer —11— of cork or equivalent heat-insulating material to reduce the transmission of heat from the exterior to the interior of the case and thereby to facilitate the maintenance of a relatively lower temperature within the case.

Each laminated section is also provided with a marginal edge —12— of wood or equivalent material surrounding the marginal edges of the adjacent cork filler —11— to firmly retain the latter in place and also to provide means whereby the sections of the bottom, top, sides and ends may be more firmly secured to each other by nails, screws or other fastening devices.

A pair of cross bars —13— are mounted upon and secured to the upper face of the

100

bottom of the case or housing —1— to extend transversely thereof in parallel spaced relation to each other and to the ends of the case, but preferably nearer the ends for receiving and supporting separate pairs of upright bars —14—, those of each pair being arranged directly over its corresponding cross bar —13— but in transversely spaced relation to each other and to the side walls of the case as shown more clearly in Figure 2.

The upright bars —14— of both pairs are spaced equal distances apart and also equal distances from the sides of the case, the space between them serving to receive a series of conduits —15— for the powdered material to be treated while the spaces between the upright bars and the upright sides of the case serve to receive separate sets of refrigerating coils —16—.

The upper ends of each pair of upright bars —14— are rigidly connected to a superposed cross bar —18— so that both cross bars —18— are disposed in the vertical planes of their respective pairs of upright bars —14— as shown more clearly in Figure 1, it being understood that the lower end of the upright bars —14— are also firmly secured to the lower cross bars —13—.

The upper cross bars —18— are therefore supported by their respective upright bars —14— and extend laterally some distance beyond said upright bars for receiving and supporting separate sets of straps —19— carrying the refrigerator coils —16—, said straps having their upper ends rigidly secured to the underside of the upper cross bars —18—.

Additional cross bars —20— are mounted upon the upper edges of the cross bars —18— for receiving and supporting a horizontal plate or shelf —21— which extends lengthwise of and within the case —1— across the intervening space between the cross bars —18— and —20— and also from side to side between the intermediate posts —3—, leaving equal spaces between the ends of the plate and upright ends of the case and also open spaces between opposite edges of the plate and inner faces of the side walls of the case between the posts, said plate being also located some distance below the top wall of the case and in a plane above the uppermost conduit —15— and uppermost pipes 55 of the refrigerator coils —16—.

The interior of the case forms an air chamber —22— in which the conduits —15— and refrigerating pipes —16— are located so as to allow free circulation of air around the refrigerator coils and also around the conduits —15—.

The means for circulating the air comprises, in this instance, a fan or blower —23— directly connected to the armature shaft of an electric motor —24— which, together with

the fan or blower —23— is mounted upon the shelf or plate —21— within the air space between said shelf and top of the case as shown more clearly in Figure 1.

This fan or blower —23— is arranged to take air from the interior case at one side and to deliver it to the interior case from the opposite side, thereby establishing a circulation of the air within the case from the fan around one end of the plate —21— downwardly around the conduits —15— and refrigerator pipes —16— and return around the other end of the plate to the other end of the blower.

The tubular conduits —15— are arranged in a vertical plane one over the other lengthwise of and midway between the opposite upright sides of the case and are successively inclined in reverse directions from top to bottom lengthwise of the case to assist in feeding the material therethrough by gravity.

The uppermost conduit —15— is provided in its upper side near its highest end with a vertical inlet pipe —25— through which the cocoa powder is fed by any suitable means so as to enter the higher end of the uppermost conduit.

The lower side of the lower end of the uppermost conduit is connected by a nipple —26— to the upper side of the higher end of the next lower conduit which, in turn, has the lower side of its other end connected by a similar nipple —26— to the upper side of the higher end of the next adjacent conduit and so on through the successive conduits having the lower side of their lower ends connected to the upper side of the higher ends of the next adjacent conduit by similar nipples —26— as shown more clearly in Figure 1.

The lower side of the lower end of the lowest conduit is provided with an outlet pipe —27— which may be connected to any repository for the dried and cooler material as it emerges from the cooling apparatus.

The upper conduit is provided with an upwardly extending vent pipe —28— leading from the top thereof near its lower end to the atmosphere through suitable openings in the plate —21— and top of the case and serving to permit the escape of air from the interiors of all of the conduits while the powdered material is being fed therethrough.

These several conduits —15— are closed at both ends by end heads —29—, each of which is provided with diametrically opposite lugs —30— bolted or otherwise secured to the adjacent portions of the upright bars —14— for holding the conduits in fixed relation at the desired angle of inclination.

Each conduit —15— contains a rotary agitator —31— extending lengthwise thereof from end to end co-axial therewith and there-

fore at the same angle of inclination thereof.

Each agitator comprises a central lengthwise shaft —33— carrying a plurality of axially spaced spiders —34— to which are secured diametrically opposite lengthwise blades —35— extending from end to end of the tubular conduits —15— as shown in Figure 1, said shafts having their opposite ends journaled in suitable bearings in the end heads of their respective conduits —15—.

10 A main driving shaft —36— is journaled in suitable bearings in one end of the case —1— and is provided with a pulley —37— adapted to be connected to any available source of power for rotating the shaft.

15 The inner end of the driving shaft —36— is provided with a pinion —38— meshing with a gear —39— on the adjacent end of the uppermost shaft —33— of the corresponding agitator.

20 Rotary motion is transmitted from the other end of the upper shaft —33— to the corresponding end of the next adjacent lower shaft by means of gears —40—, similar gears

25 —41— and —42— being provided for transmitting rotary motion in sequence from the second-named shafts to the remaining shafts —33— as shown more clearly in Figure 1.

20 The blades —35— of each agitator are arranged somewhat spirally with reference to the axes of their corresponding shafts so that the end of each blade adjacent the higher end of the corresponding conduit moves slightly in advance of the remaining portions

35 of the blades to assist in feeding the powdered material from the higher to the lower ends of the conduits but at a relatively low rate of speed to permit the rotation of the agitators to effect a thorough agitation of the powder in transit through the tubes.

40 It is now evident that as the material is introduced into the inlet conduit —25— it will be successively conveyed through the several conduits —15— in zigzag tortuous paths and will finally emerge through the outlet conduit —27—.

45 The refrigerator coils —16— are arranged in vertical rows of, in this instance three, in each row, at opposite sides of the conveyor tubes —15—, the lowermost pipe of each coil being provided with an inlet —43— which may be connected to any available source of supply for a refrigerant liquid such as ammonia, the upper pipe of each coil being provided with an outlet —44—.

50 Any suitable means may be employed for maintaining a circulation of the refrigerant liquid through the coils for the purpose of cooling said coils and the air which surrounds them and for transmitting the lowered temperatures to the conduits —15— and powdered material passing therethrough.

55 Suitable drip pans —45— are supported upon the cross bars —13— within the vat directly below the opposite sets of refrigerat-

ing coils —16— for receiving any moisture which may accumulate upon the coils and are provided with drainage outlet pipe —46— leading to any suitable soil or waste pipe, not shown.

70

Operation

The cocoa powder or other material to be cooled is fed into the inlet pipe —25— at a temperature of, say 115 degrees F., and thence passes through the successive conduits —15— in which the material is thoroughly agitated and its temperature greatly reduced by the refrigerating coils —16— until it is finally discharged from the lowermost tube into a sifter or other receptacle at a temperature of, say 50 degrees F.

75

The thorough agitation of the powdered cocoa and gradual lowering of the temperature thereof in transit through the successive tubes greatly accelerates the cooling of the powder to a uniform temperature and dryness required for its manufacture into cholate and analagous products.

80

85 It will be evident, however, that the number of conveyer tubes and agitators and also the number of refrigerating coils may be varied at will according to the production required and that the means for circulating the air around the tubes and refrigerating coils may also be modified without departing from the spirit of this invention.

90

95 What I claim is:—

1. In a device of the class described, a housing having therein a pair of chambers arranged one above the other, said chambers being in communication with each other at their outer edges, a plurality of tubular conduits connected in series and disposed in sequence in the lower chamber, rotary agitators disposed in the conduits, a plurality of cooling coils for the reception of a refrigerant disposed in the lower chamber in spaced relation to said conduits and means comprising a fan positioned in the upper chamber for circulating the air within the housing around the conduits and refrigerating coils.

100

105 2. In a device of the class described, a housing having therein a pair of chambers arranged one above the other, said chambers being in communication with each other at their outer edges, a plurality of tubular conduits connected in series and disposed in sequence in the lower chamber, the disconnected ends of the uppermost and lowermost conduits being provided respectively with an inlet and an outlet conduit, rotary agitators disposed in the conduits, a plurality of cooling coils for the reception of a refrigerant disposed in the lower chamber in spaced relation to said conduits, means comprising a fan positioned in the upper chamber for circulating the air within the housing around the conduits and refrigerating coils.

110

115 3. In a device of the class described, a housing having therein a pair of chambers arranged one above the other, said chambers being in communication with each other at their outer edges, a plurality of tubular conduits connected in series and disposed in sequence in the lower chamber, the disconnected ends of the uppermost and lowermost conduits being provided respectively with an inlet and an outlet conduit, rotary agitators disposed in the conduits, a plurality of cooling coils for the reception of a refrigerant disposed in the lower chamber in spaced relation to said conduits, means comprising a fan positioned in the upper chamber for circulating the air within the housing around the conduits and refrigerating coils and means for rotating said agitators.

120

125

130

3. In a device of the class described, a housing having therein a pair of chambers arranged one above the other, said chambers being in communication with each other at their outer edges, the upper chamber being provided with a partition extending transversely of the housing, substantially midway between the ends thereof, a plurality of tubular conduits connected in series and disposed in sequence in the lower chamber one above the other, rotary agitators disposed in the conduits, a plurality of cooling coils for the reception of a refrigerant disposed in the lower chamber in spaced relation to said conduits and means comprising a fan positioned in the partition intermediate the ends thereof for circulating the air within the housing around the conduits and refrigerating coils.

In witness whereof I have hereunto set my
hand this 16th day of March 1927.

WALTER WAIN.
